Des. 242,535
Patented Nov. 30, 1976

242,535

BUSSING CART

Frederick R. Becker III, Dallas, Pa., assignor to
Metropolitan Wire Corporation, Wilkes-Barre, Pa.

Filed Nov. 10, 1975, Ser. No. 630,735

Term of patent 14 years

Int. Cl. D12—02

U.S. Cl. D12—22

FIG. 1

FIG. 2

FIG. 3

FIG. 4

FIG. 5

FIG. 6

FIG. 7

FIG. 8

FIG. 9

FIG. 10

FIG. 1 is a perspective view of a bussing cart showing my new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a perspective view of a bussing cart showing a second embodiment of my new design;

FIG. 7 is a top plan of view of FIG. 6;

FIG. 8 is a front elevational view of FIG. 6;

FIG. 9 is a right side elevational view of FIG. 6; and FIG. 10 is a rear elevational view of FIG. 6.

I claim:

The ornamental design for a bussing cart, substantially as shown and described.
